Patented Nov. 28, 1916.

INVENTOR

William F. Lautenschlager

UNITED STATES PATENT OFFICE.

WILLIAM F. LAUTENSCHLAGER, OF CINCINNATI, OHIO, ASSIGNEE TO LORENZ MUTHER,
OF NEWTON, MASSACHUSETTS.

FOLD-PRESSER FOR FOLDING-MACHINES.

1,206,762.

Specification of Letters Patent. Patented Nov. 28, 1916.

Application filed June 26, 1916. Serial No. 105,929.

To all whom it may concern:

Be it known that I, WILLIAM F. LAUTENSCHLAGER, a citizen of the United States, residing in Cincinnati, in the county of Hamilton, State of Ohio, have invented certain new and useful Improvements in Fold-Pressers for Folding-Machines, of which the following is a specification, reference being had to the drawings accompanying the same and forming a part thereof.

My invention relates to improvements in fold pressers for folding machines, such as are used to fold over the edges of sheet material, and particularly the edges of boot and shoe parts.

The objects of my invention are as follows:—To so construct and arrange the fold presser surfaces of fold pressers that the pressing operation will be accomplished progressively; *i. e.*, so that one portion of the fold pressing surface will extend across the folded edge and a part of the width of the folded over edge and press the same, and the remainder of the fold presser surface will extend fully across the fold. There will thus be what may be termed a preliminary pressing and a complete pressing of the folded edge at each operation of the fold-presser.

Another object of my invention is to so form and arrange the fold-presser with relation to the other parts of a folding machine so as to increase the distance as much as possible between the point where the turning operation commenced on the edge and the point where the fold is completely folded over and pressed down and thereby prevent strain on the edge of the work and consequent puckering of the material at the folded line. This form and arrangement of the fold-presser results in the completed fold presenting a smooth surface on both sides of the material contiguous to the fold line.

Another object of my invention is to provide a fold-pressing surface which is capable of an adjustment approximately longitudinally of the fold-presser so that it may be adjusted in its extended position when convex curves are being folded, and returned to its withdrawn position when straight edges are being folded. The purpose of this adjustment will be more fully pointed out in the specification and appear from the drawings accompanying the same.

The purposes of, or results to be accom-

plished, by providing for a preliminary pressing of the folded edge and thereafter a complete pressing, stand out more clearly when material having straight edges are being folded over. In such cases there is a strain on the edge being folded over due to the fact that the said edge tends to occupy a greater length during the turning operation than it occupies when the material is lying flat, as will clearly appear from the drawings and description.

Other objects of my invention will appear from the description contained in this specification.

In the drawings which accompany this specification and form a part thereof—Figure 1 is a front elevation of a folding machine such as is more fully illustrated in the application for a patent executed by me on even date herewith, Serial No. 105,930, filed June 26, 1916, and in which is more fully illustrated and described the operating mechanism of the folding machine; Fig. 2 is a sectional side elevation taken through line 2—2 Fig. 1; Fig. 3 is a plan view of the top of the fold presser, a section of the material being folded, and a section of the bearing on which the fold presser is pivoted; and Fig. 4 is a plan view similar to the one shown in Fig. 3, but showing a different position of the fold-presser surfaces; *i. e.*, with the fold-presser surfaces extended in the position they occupy when folding the convex curved edge of a piece of material.

In the drawing, 1 represents the fold-presser, and 2 a bushing which is secured in an elongated hole in the fold-presser, which bushing is mounted on the bearing shaft 3; 4 is the elongated hole in the fold-presser. The purpose of this elongated hole is so that the fold-presser may move back and forth on the bushing 2, the fold-presser being held in the position shown in Fig. 2 by means of a spiral spring 5, one end of which bears and presses against the bearing bushing or sleeve 2, the other end against the end of an adjusting screw 6 which is threaded into the projecting part 1^a of the fold-presser 1. The adjusting screw 6 is used to increase or decrease the tension of the spring 5.

The fold-presser 1 is provided with a movable fold-pressing surface 7. This fold-pressing surface 7 is rectangular in form, as

indicated in Fig. 2, so as to embrace the end of the fold-presser 1 and is held in position by the screws 8 and 9 which pass through slotted holes 8^a and 9^a, as shown in Figs. 3 and 4; the slot 8^a being in the end of the fold-presser 1 and the slot 9^a in the extension 13 of the presser surface 7. This method of mounting the presser surface 7 on the fold-presser 1 permits of an endwise 10 movement of the fold-presser surface 7 approximately longitudinally of the fold-presser 1 for the purpose of adjustment. The fold-presser surface 7 is held in an inward position, as shown in Fig. 3, by means 15 of a spring 11, the end 12 of which is bent downwardly and is inserted in a hole in the fold-presser 1 and the end 14 bent upwardly and inserted in the pressing surface 7 so that the tension of the spring 11 will normally 20 hold the fold-presser surface in an inward position, as shown in Fig. 3.

In using the term "normal position" I wish it understood that this term is intended to be used in connection with the positioning of the fold-presser 7, as illustrated in the drawings. It may be desirable, however, to have the fold-presser surface held normally in extended position, or outward as shown in Fig. 4. This would occur in cases 25 where convex surfaces were being folded to a larger extent than straight portions, and in such case the spring 11 would be arranged for moving and holding the fold-presser surface 7 in its outward or extended 30 position when curved portions were being folded. The fold-presser surface 7 is provided with a rear curving portion 15 which is curved on a circle, the center of which is located at the axis of the bearing 3, as shown 35 in Fig. 2, so that the rocking movement of the fold-presser 1 produced through its connection with the pivot-point 16, the L-shaped rocker-lever 17, and the pivot 18, which is mounted in a block 19 secured in the crank 40 member 20, which is mounted in the revolving shaft 21, would not affect its position taken laterally.

The fold-presser surface 7 is adjusted longitudinally of the fold-presser 1 by means 45 of a lever 22 which has an outwardly extending arm 23, broken off in this view, but which extends outwardly so that the operator of the machine can grasp it to move it, the lever 22 being pivoted upon the pivot-screw 24. Movement of the lever 22 brings the upturned end 25 against the downturned portion 15 of the pressing surface 7 so as to move it transversely against the tension of the spring 11 and so as to extend and hold 50 said fold-pressing surface outwardly, as shown in Fig. 4. When pressure of the end 25 of the lever 22 is released from the downturned end 15 the spring 11 immediately returns the fold-pressing surface 7 to the position as shown in Fig. 3. This arrangement

allows the operator to extend or permit the withdrawal of the fold-presser 7 at will so that said fold-presser surface 7 may be used in a withdrawn position, as illustrated in Fig. 3, where straight portions of the edge 70 are being folded, and at will extend and hold said fold-presser surface 7 in such extended positions whenever and for as long a period as desired, or when curved portions, particularly convex curved portions are being 75 folded, as illustrated in Fig. 4.

My fold-presser 1 is used in conjunction with feeding means for feeding the material progressively step-by-step and its use is not limited to any particular type of feeding 80 means. In the drawings accompanying this specification, 26 is the feed-foot for feeding the material progressively step-by-step and is such as is described in my application of even date herewith, Serial No. 105,930, filed 85 June 26, 1916; and 27 is the presser-foot, and 28 the lower idler block, as illustrated in said application. Furthermore, the operating parts for the feed-foot, the presser-foot, and the fold-presser illustrated herein, 90 as well as the other parts, are as described in my said application of even date herewith. I may employ in connection with my fold-presser, slitting means, not shown, of any of the usual types employed in folding 95 machines.

In the drawing Fig. 3, the fold-presser surface is shown as operating to fold a straight edge, and the material 29 is being folded over as at 30. The portion of the 100 edge liable to strain and stretching lies between the point 31 where the fold commences, and the point 32 where the fold and pressing operations are first fully completed. If a line was drawn through the 105 point 32, and perpendicular to the fold line 36, it would be observed that the distance between the points 31 and 32 is greater than the distance between the point 31 and where the said perpendicular line would intersect 110 the fold-line 36. This increase of distance is what produces strain and stretching of the edge. Any construction of a folding machine and its folding elements, whereby the 115 distance is increased between the point where the fold commences and where it is fully completed, as between the points 31 and 32, will lessen the strain and stretching.

It is further desirable to first press down that part of the fold near the fold-line. By 120 doing so it tends to prevent puckering at the fold-line, which is very undesirable. By having the end of the pressing surfaces stepped, preferably as shown at 34 and 35, it results in pressing the part of the fold under the surface 34 in advance of the completion 125 of the pressing operation by the pressing surface 35.

It will be understood that it is usual to coat the contact surfaces of the fold previous 130

to the folding operation so the folded-over portion will adhere to the body of the material as the fold-pressing operation is performed. Usually a folding or edge-turning block 37 is used to turn over the edge to be folded.

In Fig. 4, my fold-presser is illustrated as folding and pressing a convex curved edge of material, and the pressing surfaces 7 shown as adjusted to its extended position. To fold convex curves it is necessary to extend the fold-pressing surface 7 because the curved edge 38 draws away from the pressing surface as it is folded and the fold-pressing surface 7 would not reach fully across the fold unless it was moved to its extended position.

My invention as illustrated and described in the drawings and the specification is directed broadly to the fold-pressing means and the extensible fold-presser surface with or without the plurality of steps, as shown.

I do not limit myself to the exact form of the parts of the fold-presser and fold-presser-surfaces, or to the exact arrangement of the parts, or arrangement of the adjusting mechanism.

What I claim is—

1. In a folding machine, means for feeding and means for folding over the edge of sheet material, and a fold-presser for pressing down the folded edge having a fold-pressing surface adjustably mounted thereon and arranged to be adjusted approximately longitudinally of the fold-presser and approximately laterally across the line of fold.

2. In a folding machine, means for feeding and means for folding over the edge of sheet material, a fold-presser for pressing the folded edge having a fold-pressing surface adjustably mounted thereon and arranged to be adjusted approximately longitudinally of the fold-presser, and means for moving the fold-pressing surface into its adjusted position.

3. In a folding machine, a fold-turning block, and a fold-presser for pressing the folded edge having an adjustable fold-presser surface adjustable approximately 50 longitudinally of the fold-presser.

4. In a folding machine, means for folding over the edge of sheet material, and a fold-presser having an adjustable stepped fold-presser surface adjustable approximately 55 longitudinally of the fold-presser for pressing down the folded edge.

5. In a folding machine, means for turning over the edge of sheet material, a fold-presser having an adjustable fold-presser 60 surface adjustable approximately longitudinally of the fold-presser, and means for adjusting said fold-presser surface to the desired position.

6. In a folding machine, feeding means, 65 edge-turning means, and a fold-presser having an adjustable fold-presser surface adjustable approximately longitudinally of the fold-presser, the said fold-presser surface being stepped, and means for adjusting the 70 said fold-presser surface into and holding it in the desired position.

7. A folding machine having means for feeding, means for turning the edge of material, and means for pressing the turned over 75 edge, comprising a fold-presser surface formed and arranged so that it can be moved longitudinally in order that a portion of said fold-presser surface will progressively 80 press the bight of the fold and a portion of its width and the remainder of said pressing surface will progressively press the full width of the folded over edge.

In testimony whereof, I have hereunto set my hand, in the presence of two subscribing 85 witnesses, this the 13th day of June, A. D. 1916.

WILLIAM F. LAUTENSCHLAGER.

Witnesses:

R. P. ELLIOTT,
H. M. KELSO.

It is hereby certified that in Letters Patent No. 1,206,762, granted November 28, 1916, upon the application of William F. Lautenschlager, of Cincinnati, Ohio, for an improvement in "Fold-Pressers for Folding-Machines," errors appear in the printed specification requiring correction as follows: Page 2, line 73, for the word "positions" read *position*; page 3, line 80, claim 7, for the word "if" read *of*; and that the said Letters Patent should be read with these corrections therein that the same may conform to the record of the case in the Patent Office.

Signed and sealed this 26th day of December, A. D., 1916.

[SEAL.]

R. F. WHITEHEAD,
Acting Commissioner of Patents.

Cl. 12—55.
